JOHN F. PETERS, OF EDGEWOOD PARK, PENNSYLVANIA, ASSIGNOR TO WESTINGHOUSE ELECTRIC & MANUFACTURING COMPANY, A CORPORATION OF PENNSYLVANIA.

SYSTEM OF DISTRIBUTION.

Application filed May 24, 1923. Serial No. 641,072.

My invention relates to alternating-current systems of distribution and it has particular relation to constant-current systems employed for series lighting and the like.

5 More particularly, my invention relates to systems in which current of constant value is derived through a plurality of reactive devices connected alternately in circuit with a source of constant potential.

10 The object of my invention is to provide means for protecting the system from excessive voltage strains occasioned by accidental interruption of the constant-current circuit.

15 It is known that when four elements offering equal reactances to currents of the same frequency, two of said elements being condensive and two being inductive, are so connected in a closed circuit as to alternate in

20 position with one another, and an alternating-current voltage of constant value and the proper frequency is impressed across two opposite points of the closed circuit, current of constant value may be obtained

25 in a single circuit that is connected across the other two opposite points of the closed circuit. This arrangement of reactance elements, in which the current flowing in the constant-current receiving circuit is main-

30 tained under certain conditions 90° out of phase relation with the constant voltage impressed by the constant-potential supply circuit has been termed a "monocyclic square".

When a series lighting circuit is directly connected to this source of constant current, dangerous voltage conditions may result if the lighting circuit is accidentally interrupted. To overcome this difficulty, I propose to interpose a transforming device of such character as to suitably limit the voltage rise upon the occurrence of said open circuit.

35 My invention will be best understood by reference to the accompanying drawing, in which

Figure 1 is a diagrammatic view of circuits and apparatus embodying my invention.

40 Fig. 2 represents, diagrammatically, a modification of the system of Fig. 1, and

Fig. 3 is a plan view representing a convenient arrangement of circuits and apparatus embodied in my invention.

45 Referring to Fig. 1, a series lighting cir-

cuit comprising a plurality of lamps 1 is 55 connected, by means of conductors 2 and 3, to opposite points of a closed circuit or monocyclic square 4, comprising reactive elements 5, 6, 7 and 8, the elements 5 and 6 being inductive reactors that have identical 60 electrical characteristics and the elements 7 and 8 being condensers having identical electrical characteristics, the several elements alternating in position to form the closed circuit 4. Alternating-current energy is derived from a source of constant potential 65 comprising line conductors 9 and 10, and the constant current derived from circuit 4 is supplied to conductors 2 and 3 through a protective device comprising an auto-transformer 11, provided with taps to take 70 care of variations in supply voltage.

In Fig. 2 I have employed, in lieu of the auto-transformer 11, a single-phase distributing transformer 21 of a familiar type. In 75 either case, the transformer is provided with an iron core that is worked at fairly high flux density under normal operating conditions. Any other suitable reactance device 80 may be employed having this necessary saturation feature.

When constant-potential energy is supplied to conductors 9 and 10, current of constant value is derived and traverse conductors 2 and 3 of the series lighting circuit. Upon 85 the accidental interruption of the latter circuit, the derived or secondary voltage will increase only sufficiently to make the magnetizing current of the transformer 11 or 21 equal to the normal line current. On account of the saturation characteristic of the transformer, I have been able to limit this 90 voltage to approximately 50% in excess of normal line voltage that is impressed upon the reactance elements 5, 6, 7, and 8. Without this arrangement, that is, when the transformer 11 or 21, is omitted and conductors 95 2 and 3 are connected directly to the opposite corners of the circuit 4, it is found that the voltage occasioned upon the interruption of the lighting circuit is sufficiently high to damage the reactance devices or injure the insulation of the various conductors, since there is then no provision for absorbing this 100 voltage.

In Fig. 3, I have illustrated a convenient outdoor arrangement for mounting the required apparatus, which includes oil tanks

12 and 13 containing the reactive elements 5, 6, 7 and 8 and mounted, as transformer tanks are customarily mounted, upon cross arms 14 and 15 supported by a pole 16.

5. The simplicity and efficiency of my invention will be apparent from the foregoing description and the invention should find ready application for the reasons set forth. I find preferable the arrangement of Fig. 1 in 10 which taps are provided to take care of variations in supply voltage. Also, I find that the monocyclic square may be constructed for its maximum economy, that is, as best suited for the requirements of any 15 particular installation, and all necessary provisions to procure current of proper value for the lighting circuit are obtainable by the suitable adjustment of the auto-transformer. I avoid the use of a moving-coil 20 type of transformer and provide apparatus better adapted to out-of-door installations.

Various modifications of my invention may be made by those skilled in the art without departing from the spirit and scope 25 of my invention and I desire, therefore, to be limited only in accordance with the appended claims.

I claim as my invention:

1. In a system of distribution, the combination with a monocyclic square for converting constant potential to constant current, of means comprising a substantially saturated transformer connected to certain 30 corners of said square and receiving constant current therefrom for inherently determining the maximum potential upon said square when the constant current circuit is interrupted.

2. The combination with a source of alternating current of constant potential and a load circuit, of a plurality of reactive devices connected alternately in circuit with 40 said source and arranged in a closed circuit to supply the load circuit with current of constant value, a substantially saturated transformer connected to points of 45 opposite polarity in said closed circuit, and

energy-consuming means comprising said load circuit connected to said transformer, said transformer functioning to limit to a 50 predetermined value the voltage strain occasioned by the interruption of said load circuit.

3. A current-transforming network comprising capacitative and inductive reactance 55 devices so assembled as to transform constant-potential alternating-current energy to substantially constant-current alternating-current energy, said network having constant-potential terminals and constant-current terminals, an iron-core transformer having primary terminals and secondary terminals, said primary terminals being connected across the constant-current terminals of said network, said transformer being substantially saturated when normal load conditions exist at the secondary terminals thereof and being capable of receiving, as magnetizing current, the full constant-current output of said network for inherently 70 determining the maximum potentials obtained when the secondary circuit of the transformer is open-circuited.

4. An alternating-current system comprising a variable load circuit requiring substantially constant currents as variable voltages, a substantially constant-current source adapted to supply substantially constant currents at variable voltages, said source being of such nature as to develop dangerously 80 high voltages if open-circuited, and an iron-core transformer connected between said source and said load circuit, said transformer operating near saturation under normal load conditions and being capable of receiving, 85 as magnetizing current, the full constant-current output of said source for inherently determining the maximum potentials obtained when the load circuit is open-circuited. 90

In testimony whereof, I have hereunto subscribed my name this 14th day of May, 1923.

JOHN F. PETERS.
